UNITED STATES PATENT OFFICE.

JOHN P. SMITH, OF NEW HAVEN, CONNECTICUT, ASSIGNOR OF ONE-HALF
TO EDWARD F. SMITH, OF SAME PLACE.

DESIGN FOR A PARCEL-CARRIER.

SPECIFICATION forming part of Design No. 27,617, dated August 31, 1897.

Application filed July 14, 1897. Serial No. 644,577. Term of patent 3½ years.

To all whom it may concern:

Be it known that I, JOHN P. SMITH, a citizen of the United States, residing at New Haven, in the county of New Haven and State 5 of Connecticut, have invented a new and original Design for Parcel-Carriers, of which the following is a specification.

Reference is to be had to the accompanying drawings, forming a part of this specification, 10 in which similar characters of reference indicate corresponding parts in both views.

Figure 1 is a perspective view of a parcel-carrier showing my new design, and Fig. 2 is a plan view thereof.

This parcel-carrier is to be used in connection with bicycles; and the leading or material feature of my design consists in a central loop 1 and return lateral arms 2, terminating in hooks 3. The lateral arms are shown as diverging, and the hooks are outwardly or 15 laterally inclined.

I claim—

The design for a parcel-carrier, substantially as shown and described.

JOHN P. SMITH.
